UNITED STATES PATENT OFFICE.

CHARLES R. WALDRON AND STEPHEN G. STEVENSON, OF ELYRIA, OHIO.

BATHING SHOE.

Application filed May 1, 1925. Serial No. 27,142.

To all whom it may concern:

Be it known that we, CHARLES R. WALDRON and STEPHEN G. STEVENSON, both citizens of the United States, residing at Elyria, 5 in the county of Lorain and State of Ohio, have invented certain new and useful Improvements in Bathing Shoes, of which the following is a specification.

Our invention relates to bathing shoes, or 10 slippers and more particularly to such devices having an enlarged toe to assist the wearer when swimming.

An object of our invention is to provide a light fabric swimming shoe or slipper with 15 an enlarged toe portion which is held in shape by a stiff reinforcing element extending around the edge thereof.

Another object of our invention is to construct a swimming shoe which may be easily 20 and quickly adjusted to the foot of the wearer and which will be held securely thereon while in use.

A further object of our invention is to provide a swimming shoe which is extremely 25 simple in construction and inexpensive to manufacture.

Other objects and advantages will become 30 apparent from the following description and drawings of an embodiment of our invention in which like numerals are employed to designate like parts throughout the same.

In the drawings—

Fig. 1 is a plan view of one embodiment of 35 our invention;

Fig. 2 is a side elevation of the shoe showing how the same is secured to the foot of the wearer, and

Fig. 3 is a plan view of a portion of a 40 second embodiment of our invention in which the tongue is adjustable on the cross strap.

In Figs. 1 and 2 of the drawings illustrating an embodiment of our invention, 5 represents the upper and 6 the sole portion. 45 These portions are formed of a waterproof light fabric such as waterproofed canvas or the like, the upper of the shoe being preferably formed of a double thickness of material. The outer edges of the shoe upper are 50 folded over a stiff frame 7 of wire or the like and are stitched along the inside of the frame together with a strip of binding material 8 as at 9. It is the purpose of the frame to provide a rigid means for stretching and 55 maintaining the shape of the toe portion substantially flat when in use and to rein-

force the edges of the upper and sole portions. The binding 8 serves to further reinforce the periphery of the shoe, while a metal clip 10 may be secured to the extreme 60 toe end of the frame to prevent undue wear at this section of the shoe. The toe portion is normally subjected to great wear especially in walking in the water where the bed contains shells or broken glass. The clip 10 not 65 only protects the stitching and binding at the toe, but also reduces water friction at that point.

The sole portion 6 is sewed to the inner edge of the upper at 12, 13 and 14. The 70 upper 5 is preferably formed to provide a tongue 15 to which is secured a strip of elastic or other material 16. The binding 8' is stitched to and extends around the tongue edges and connects with the binding 75 8. The ends of the strip 16 are sewed to the end portions 17 and 18 as at 19. The length of the strip 16 is sufficient to be arched when bridging the gap formed by the portions 17 and 18 so that it will comfortably conform to the arch of the foot of the wearer. A second strip of like material, preferably elastic, is sewed to the strip 16 at 20 and 21 so that it forms a back heel 80 strap 22.

When it is desired to wear the swimming shoe or slipper, the foot of the wearer is inserted through the opening formed by the strips 16 and 22 and thence into the pocket formed by the sole 6 and the upper 5. The 90 strap 16 will conform to the arch of the foot while the strip 22 will firmly but comfortably grip the rear upper portion of the wearer's heel, forming a positive means of securing the device to the foot.

In Fig. 3 we show a modification of the shoe just described. In this modification it will be noted that we provide a strap 23 sewed to the tongue 15 at 24 and 25. The edges of the strap are reinforced by binding 100 material 26 as shown. The strip 16 is threaded between the strap 23 and the tongue body 15 as shown in the drawing, whereby additional adjustment may be secured by the tongue and strip.

Although we have described the portion 5 as being an upper for the shoe, it is obvious that the under side of the upper 5 not forming the walls of the foot enclosure will serve as an auxiliary sole portion, and 110 will present a substantially flat surface to aid the user in swimming.

Thus it will be seen that we have provided a swimming shoe or slipper that is very simple of construction and may be very readily slipped on and off the foot of the wearer without the use of bothersome laces and other fastening devices.

It will also be seen that we have provided a means of securing the device to the wearer's foot without danger of the same becoming displaced while in use.

It will be understood that various changes in the construction of this invention may be made without departing from the spirit of the invention or the scope of the subjoined claims.

We claim—

1. A swimming shoe comprising an enlarged fabric upper, a sole portion, a wire frame attached to and extending substantially around the periphery of said upper, and elastic means secured to the said upper to firmly secure the shoe to the wearer's foot.

2. A swimming shoe comprising a substantially flat enlarged fabric upper, a sole portion, a wire frame attached to and extending substantially around the periphery of said upper portion to normally stretch the same, a tongue formed on the upper, and elastic means associated with the tongue and upper edges to secure the shoe to the foot of the wearer.

3. A swimming shoe comprising a substantially flat upper portion, a sole portion, a wire frame attached to and extending sub-

stantially around the periphery of said upper portion to normally stretch the same, a tongue formed on the upper, and a strip of elastic material secured to the upper adjacent its rearward outer edges, and a strip of elastic material secured to the ends of said first named strip substantially at right angles thereto, said strips being normally arched when not in use.

4. A swimming shoe comprising an enlarged flattened fabric upper, a sole portion, a frame attached to and extending substantially around the periphery of said upper portion to normally stretch the same and maintain it in a flattened condition, a tongue formed on the upper, a strip of elastic material secured to the upper adjacent its outer edges, and a strip of elastic material secured to the ends of said first named strip substantially at right angles thereto, said strips being arched approximately at right angles to each other when not in use.

5. A swimming shoe comprising an upper, a sole portion, a wire frame attached to and extending substantially around the periphery of said vamp portion, an auxiliary sole portion secured to said first named sole portion, and elastic means associated with the upper for securing the shoe to the wearer's foot.

In testimony whereof we hereunto affix our signatures this 21st day of April, 1925.

CHARLES R. WALDRON.
STEPHEN G. STEVENSON
